CLAIM

The ornamental design for a holder for a fire-starter rod and a combustible material, as shown and described.

DESCRIPTION

FIG. 1 is a perspective view of a holder for a fire-starter rod and a combustible material showing my new design; FIG. 2 is a right-side elevational view thereof; FIG. 3 is a left-side elevational view thereof; FIG. 4 is a front elevational view thereof; FIG. 5 is a rear elevational view thereof; FIG. 6 is a top plan view thereof; FIG. 7 is a bottom plan view thereof; and, FIG. 8 is an exploded view thereof.

The broken lines immediately adjacent the shaded areas represent the bounds of the claimed design while all other broken lines are directed to a fire-starter rod; the broken lines form no part of the claimed design.
